ADDING AND LISTING MACHINE

Loring Pickering Crosman, Maplewood, N. J., assignor to Gardner Company, Orange, N. J., a corporation of Delaware

Application June 19, 1936, Serial No. 86,071

2 Claims. (Cl. 197—126)

The invention has relation to adding and listing machines, of the type wherein statement sheets are printed and a record of the entries is kept upon a separate tally strip. More particularly the invention relates to means for facilitating the feeding of the tally strip into a machine employing two ink ribbons, one for printing upon the statement sheet and the other upon the tally strip.

10 The invention consists in the novel construction and combination of parts as set forth in the appended claims.

As illustrated, the invention is shown as applied to a Gardner adding and listing machine, or "listing calculator", such as disclosed in U. S. Patent No. 1,946,572, issued on February 13, 1934 to the present inventor.

In the accompanying drawings, illustrating the invention:

20 Fig. 1 is a vertical section through the paper feeding means of an adding listing machine equipped with the present invention.

Fig. 2 is a front elevation of the tally strip feed devices and ink ribbon mechanism.

25 Fig. 3 is a plan view of the ribbon and printing hammer mechanism.

Fig. 4 is a detail front view of the tally strip tear-off plate.

30 In these drawings the numeral 1 designates a cylindrical platen, to which the statement sheets are fed over a guide plate 2. Between this platen and the type bars 3 are located a pair of ribbon guides 4, 4 adapted to hold two ribbons 5 and 6 in parallel position across the printing line. The ribbon guides 4 are designed to hold the ribbons 5 and 6 in spaced relation, and to provide a channel between the ribbons for guiding the tally strip 7.

40 The tally strip is inserted in a carrier 8 on the base of the machine in roll form, and is guided from the carrier between a feed roll 9 and a cooperating idler roll 10, whence the strip is fed between plates 11 and 12 and a guide chute into proximity to the lower ends of the ribbon guides 4. The ribbon guides may be adjusted vertically in the usual manner to provide for two color printing, and an interval is left between the upper edge of the plates 11 and 12 and the ink ribbons, and in order to bridge this interval these plates are each provided on one side with an extension 13 whereby one edge of the strip will be guided into place between the lower branches of one of the ribbon guides 4, these branches completing the guiding of this edge of

the strip into the interval between the ribbons 5 and 6.

From the ribbon guides 4 the tally strip is fed upward over a roller 14 to position immediately in rear of a tear-off plate 15. Plate 15, as seen in Fig. 4, is provided with an oblique tearing edge 20 the upwardly projecting end of which is in line with the extensions 13 of the guide plates 11 and 12. Therefore, when a section of the tally strip is torn off, the remaining portion of the strip will be left with an oblique edge, so that in case it is desired to temporarily feed back the strip out of the machine, it may be reinserted by the operation of the feed roll 9, one side of the paper, the right hand side as shown, being guided upward between the extensions 13 and the rest of the strip following into position in the channel of the ribbon guides 4 without further manipulation on the part of the operator.

One utility of this feeding means will be in 20 cases where a portion of the work to be done on the machine requires the printing of a record on the tally strip and where other work, to be done from time to time, requires printing upon the statement sheets only. Another utility is in connection with work, some of which is to be recorded both upon the statement sheet and upon the tally strip, and in which other work is to be recorded upon the tally strip only. In this latter case, it is desirable to feed the tally strip back from between 30 the ribbons 5 and 6 and to reinsert the strip between the ribbon 6 and the platen 1, so that the platen may not become inked by the ribbon 6.

In order further to facilitate the changing of the tally strip to the last named position, a deflector plate 16 is hinged in position above the cut-out portion of the guide plate 11, the plate 16 being normally held in the position illustrated in Fig. 1 by means of a spring 17. In this position, plate 16 forms a continuation of the plate 11 and 35 the tally strip will be fed up between the ribbons 5 and 6 in the manner hereinbefore described. When it is desired however to feed the tally strip up between the ribbons 6 and the platen 1, a crank extension 18 of the pivot rod 19 of plate 16 is held 40 in rearward position by the operator, against the tension of spring 17, the plate 16 being thus held with its free edge in contact with the plate 12, so that upon the feeding of strip 7 by the roll 9, the strip will be deflected out of the upper end of 45 the chute, passing above plate 16 and upwardly between the platen 1 and the ribbon guides 4. From this point, the strip is carried over the roller 14 and in rear of the tear-off plate 15 as before. Upon release of crank 18 by the operator spring 50 55

17 will move plate 16 back to its normal position, so that at the next withdrawal and reinsertion of the strip, the parts will act to guide said strip back between the ribbons 5 and 6, unless the operator again moves the crank 18.

5 I claim:

1. In an adding and listing machine provided with a platen and two parallel, spaced printing ribbons; a roll paper feeding device comprising a 10 guide plate adapted to direct the paper strip between said ribbons, and an adjustable plate adapted to deflect the strip to pass the same between the ribbons and the platen.

2. In an adding and listing machine provided with a platen and two parallel, spaced printing ribbons; a roll paper feeding device comprising a guide plate, a hinged plate, and a spring normally holding said plate in position to cooperate with 5 the first-named plate to direct the paper strip between said ribbons, said hinged plate being adjustable, against the tension of its spring, to deflect the strip to pass between the ribbons and the platen.

10

LORING PICKERING CROSMAN.
